DESIGN FOR A PUSH GUARD

Fred L. Vernon, Newton, Iowa

Application November 19, 1934, Serial No. 54,080

Term of patent 7 years

To all whom it may concern:

Be it known that I, Fred L. Vernon, a citizen of the United States and a resident of Newton, in the county of Jasper and State of Iowa, have invented a new, original, and ornamental Design for a Push Guard, of which the following is a specification, reference being had to the accompanying drawing, forming part thereof.

Figure 1 is a front elevation of a push guard embodying my new design.

Figure 2 is a rear elevation of the push guard. Figure 3 is a central, vertical sectional view of the same; and

Figure 4 is an elevation of the push guard.

I claim:

The ornamental design for a push guard, substantially as shown.

FRED L. VERNON.
